CLAIM

The ornamental design for a floating basketball hoop, as shown and described.

DESCRIPTION

FIG. 1 is a top, front, right side perspective view of a floating basketball hoop showing my new design;
FIG. 2 is a bottom, rear, left side perspective view thereof;
FIG. 3 is a front view thereof;
FIG. 4 is a back view thereof;
FIG. 5 is a left side view thereof;
FIG. 6 is a right side view thereof;
FIG. 7 is a top plan view thereof;
FIG. 8 is a bottom plan view thereof; and,
FIG. 9 is an enlarged view of the area labeled 9 in FIG. 1. The broken lines in the drawings depict portions of the floating basketball hoop that form no part of the claimed design.

1 Claim, 9 Drawing Sheets
